UNITED STATES PATENT OFFICE.

LOUIS SCHWARZ, OF BROOKLYN, NEW YORK.

DESIGN FOR A BOX.

SPECIFICATION forming part of Design No. 21,955, dated November 1, 1892.

Application filed September 2, 1892. Serial No. 444,905. Term of patent 3½ years.

To all whom it may concern:

Be it known that I, LOUIS SCHWARZ, a citizen of the United States, and a resident of Brooklyn, in the county of Kings and State of New York, have invented a certain new Design for a Box for Candy and other Articles, of which the following is a specification.

In the accompanying drawings, Figure 1 is a perspective view of a box for candy or other articles, showing my design; and Fig. 2 is a vertical transverse sectional view of the same.

The leading feature of my design consists in a box in the shape of an egg and a cover on the same in the shape of a head.

A is the box, in the shape of an egg.

B is the cover, in the shape of a head. D is a neck-band; E, a cross on the neck-band; and F is a bow on the lower front part of the box.

Having thus described my invention, I claim as new and desire to secure by Letters Patent—

The design for a box for candy or other articles, substantially as herein shown and described.

In testimony that I claim the foregoing as my invention I have signed my name in presence of two subscribing witnesses.

LOUIS SCHWARZ.
